SUPERHEATER BOILER

Charles W. Gordon, Munster, Ind., assignor to
The Superheater Company, New York, N. Y.

Application April 1, 1933, Serial No. 663,959

10 Claims. (Cl. 122—478)

The present invention relates to superheater boilers of the type having lanes through its front bank some perpendicular to the furnace face and some parallel thereto.

Many boilers have had superheater elements interspersed among the tubes of the generating banks. Such arrangements have been very successful, but the ever advancing requirements of practice have indicated the desirability of improving them in certain directions.

It is an object of my invention to provide an arrangement adapted to better utilize the available space in superheater boilers so as to permit somewhat higher steam temperatures with a given amount of superheater surface in a given boiler or to permit greatly increasing the steam temperatures without much increase of the space required.

In order that my invention, together with its objects and advantages, may be readily and fully understood, I will now describe in detail, by way of example and in connection with the accompanying drawings, several arrangements of superheater boiler within the scope of my invention.

25 In the drawings,

Fig. 1 is a sectional elevation of a superheater boiler in accordance with my invention.

Fig. 2 is a section on the line 2—2 of Fig. 1.

Fig. 3 is a view similar to Fig. 2, but illustrating a slightly different arrangement of generating tubes and superheater elements.

Fig. 4 is also similar to Fig. 2 but illustrates a further modification of tubes and elements.

The superheater boiler illustrated in Figs. 1 and 2 is designated by reference character 10. Boiler 10 is of the Stirling type having a front generating bank 12 of vertically inclined water tubes 14, 14. The tubes 14 are arranged, as best shown in Fig. 2, to provide two sets of lanes through the bank. In Fig. 2, as well as in Figs. 3 and 4, the furnace face of the bank 12 is indicated by arrows 16 which are placed at the point of entrance of the furnace gases into the bank. As shown in Fig. 2, the lanes between the tubes 14 are in two sets, one set 18, 18 being at right angles to the furnace face of bank 12 and the other set 20, 20 running parallel to the furnace face of such bank. It will be seen further that the distance between tube centers perpendicular to the furnace face of the bank is the same as that between the tube centers in a direction parallel to the furnace. Interspersed between the generating tubes 14 and substantially in two adjacent lanes 20 are two groups of superheater units 21, 21 each composed of a group of two

loops 22, 22. The units 21 preferably are placed at intersections of lanes 18 and 20 and only minor portions of such units need project outside of the lanes 20. The loops 22 are arranged diagonally with respect to the lanes 18 and 20 so that a leg of one loop of a given unit lies substantially in front of one leg of the other loop of such unit in the center line of a given lane 18, the other two legs of a given unit lying partly out of the lane 18 but wholly within the intersecting lane 20. 60

As will be apparent from comparing Figs. 1 and 2, each unit comes off the saturated header 24 so that the steam runs from such header downwardly in the leg *a* of each unit as far as the return bend 26, thence upwardly through the leg 70

b (this appearing only in Fig. 2), into the return bend 28 (this appearing only in Fig. 1), thence across to the leg *aa* in which the steam again flows downwardly into the return bend 30, and thence upwardly through the leg *bb* to the header 75

32 for superheated steam. Each of the units 21 will, of course, be understood to be substantially like every other unit. As shown in the drawings, none of the units are closer to the furnace face than the second row 20 from such face. However, 80

I do not limit myself to this. All the units are, however, preferably grouped so that the range of gas temperature over the entire superheater shall vary within the minimum limits to thereby produce a high average steam temperature from a 85

given amount of superheater surface, the arrangement of the units so as to have groups of two loops each and adapted to be each installed at the junction of two lanes at right angles permitting such grouping of the loops. While I have 90 shown the units as having only two loops apiece, I do not limit myself to this, as two groups of loops may easily be connected together to make units each having four loops.

The arrangement illustrated in Fig. 3 differs from that shown in Fig. 2 in that the generating tubes 14 of the bank 12A do not all have the same spacing in the direction parallel to the furnace face. In Fig. 3, the lanes 20, 20 are all the same size and are the same size as those in Fig. 2. 95 The lanes at right angles to the lanes 20 of Fig. 3 are not all the same width, however, some such lanes, designated 18, having the same width as those in Fig. 2, whereas every other lane in bank 12A running at right angles to the furnace face, 100 designated 18A, is narrower than the lanes 18 and lanes 20. Such an arrangement having alternate lanes 18 and 18A is well known in Stirling type boilers. With such an arrangement of generating tubes 14, it is inconvenient to use units 105

of the same general type as units 21 at the intersections of lanes 20 with lanes 18A. I have therefore illustrated in Fig. 3 two types of units, one type designated 21A and the other type designated 34. Units 21A have the same general arrangements as units 21, but may be given a greater span parallel to lanes 20 than was given units 21. The reason for such greater span will presently appear. The units 34 comprise two loops each, and the loops of each unit lie in a given plane on the center line of one of the lanes 18A. The arrangement of units 34 altogether in planes at right angles to the furnace face provides more room in the lanes 20 for the units 21A and I have therefore taken advantage of this fact in the arrangement illustrated in Fig. 3 to make the return bends 26A and 30A of larger radius than the bends 26 and 30 (Fig. 2), thereby spacing the legs *b* and *aa* farther apart. The other two legs of the units 21A, however, retain the same relative positions in Fig. 3 as such legs in Fig. 2, lying substantially on the center lines of the lanes 18.

The arrangement of the tubes 14 and the bank 12B, illustrated in Fig. 4, differs from that shown in Fig. 2 and also from that shown in Fig. 3 in that the tubes 14 are equally spaced in the direction parallel to the furnace face by the same amount as in Fig. 2 but have a greater distance between centers in the direction perpendicular to the furnace face so that the lanes 20A are wider than the lanes 18, the lanes 20 being, however, all of the same width. With such arrangement of the generating tubes 14, I am able to employ units 21B of the same arrangement throughout the tube bank. Units 21B are quite similar to units 21A, but advantage is taken of the distance between tubes 14 in the direction parallel to lanes 18 to put a leg of each of two adjacent units 40 on the center line between two adjacent tubes 14 in the direction of lanes 18. That is to say, as shown in Fig. 4, leg *b* of one unit lies alongside of the leg *aa* of an adjacent unit in the same lane 20A. Otherwise units 21B are the same as units 21 and 21A.

It will be seen that, while units 21, 21A and 21B all lie principally in lanes parallel to the furnace faces of the banks 12, 12A and 12B, the centers of all such units lie substantially at points of intersection between lanes parallel to the furnace faces and lanes perpendicular to such faces. It will be seen further that in each of the figures, the units 21, 21A and 21B all have the loops of which the units are composed lying in planes inclined both to the lanes 18 and to the lanes 20 and 20A respectively.

It will be seen that the arrangements of generating tubes and superheater units herein described permit obtaining greatly increased steam temperature as compared to one having its superheater units only in planes perpendicular to the furnace face without unduly restricting the available area for gas flow and without requiring a much deeper bank. Furthermore, the required surface being condensed into a smaller, and therefore hotter, gas zone the variation of steam temperature with load will be less while less total surface is required for a given total steam temperature.

70

What I claim is:

1. The combination of a boiler having a bank of generating tubes arranged to provide a group of lanes in such bank in a direction at right angles to the furnace face of the bank and to provide another group of lanes parallel to such face, and superheater units in said lanes, certain of said units each having a group of loops at the intersection of a lane at right angles to said face with one parallel thereto and substantially within the width of the lane parallel to said furnace face. 80
2. The combination as set forth in claim 1 and in which the units therein described are arranged in two adjacent lanes lying parallel to the furnace face of the bank. 90
3. The combination as set forth in claim 1 and in which a leg of one loop of a given unit and one leg of the adjacent loop of such unit lie substantially in the central line of the lane perpendicular to the furnace face and the other two legs of such loops lie on opposite sides of said line and in the lane parallel to the furnace face. 95
4. The combination as set forth in claim 1 and in which certain of the lanes perpendicular to the furnace face are narrower than others together 100 with multi-loop units having their loops in the same narrow lane perpendicular to the furnace face and centrally of such lane.
5. The combination as set forth in claim 1 and in which the lanes parallel to the furnace face 105 are wider than those perpendicular to such face together with units as described in claim 1 but which have legs of two different adjacent units overlapping in the direction parallel to the furnace face. 110
6. The combination of a boiler having a bank of generating tubes arranged to provide a group of lanes in such bank in a direction at right angles to the furnace face of the bank and to provide another group of lanes parallel to such face, 115 and superheating units in said lanes, certain of said units each having a group of loops at the intersection of a lane at right angles to said face with one parallel thereto and substantially within the width of the lane parallel to said furnace face, each loop of said certain units lying in a plane inclined to all said lanes. 120
7. The combination as set forth in claim 6 and in which at least one leg of each loop lies entirely within a lane parallel to the furnace face. 125
8. The combination as set forth in claim 6 and in which each loop has a leg in alignment with one of the other loops of the same unit in the direction parallel to the furnace face. 130
9. The combination as set forth in claim 6 and in which each unit has a leg of one of its loops lying in alignment with a leg of another unit in the direction perpendicular to the furnace face and in the space between two adjacent water tubes. 135
10. The combination as set forth in claim 6 and in which a leg of one loop of a given unit and one leg of the adjacent loop of such unit lies substantially in the central line of the lane perpendicular to the furnace face and the other two legs of such loops lie on opposite sides of said lane and in a line perpendicular to the furnace face. 140

CHARLES W. GORDON.
